[57] **CLAIM**

The ornamental design for a bicycle stand for single
bicycle, as shown and described.

DESCRIPTION

FIG. 1 is a perspective view of the bicycle stand for
single bicycle showing my new design;

FIG. 2 is a side elevational view thereof, the opposite
side being a mirror image of that shown;

FIG. 3 is a top plan view thereof;

FIG. 4 is a front elevational view thereof;

FIG. 5 is a rear elevational view thereof; and,

FIG. 6 is a bottom plan view thereof.
